DIFFUSING GRILLE

Arthur Ennis Prince, Boonton Township, Morris County, N. J., assignor to Otis Elevator Company, New York, N. Y., a corporation of New Jersey

Application March 29, 1955, Serial No. 35,273

Term of patent 14 years

(Cl. D54—2)

FIG. 1

I claim:

The ornamental design for a diffusing grille, substantially as shown and described.
